SERVOMOTOR CONTROL APPARATUS FOR
ELECTRIC FURNACES AND THE LIKEWoodruff A. Morey, Park Forest, Ill., assignor to
Whiting Corporation, a corporation of Illinois

Application November 25, 1952, Serial No. 322,455

14 Claims. (Cl. 314—61)

1

This invention has reference to patent application, Serial No. 299,294, filed July 16, 1952, and refers to a hydraulic-electric control adapted to impart movement to a servomotor proportional to a change in the condition of an electrical circuit. It is particularly adapted for use in regulating the electrode current of a direct arc multi-phase electric melting furnace of the type having movable electrodes.

One of the principal objects of this invention is to provide a sensitive, durable control which is low in cost, easily maintained, resistant to hunting and particularly adapted for use in connection with a novel type of hydraulic servomechanism defined in said patent application, Serial No. 299,294.

A further object of this invention is the provision of a control of the type described capable of operating efficiently under virtually all conditions.

Other objects, as well as many of the advantages of this invention, will be described in the course of the following description and in the appended drawings, in which:

Fig. 1 illustrates diagrammatically the application of the subject invention to a direct arc electric melting furnace;

Fig. 2 is a schematic electrical diagram of the subject invention;

Fig. 3 illustrates a modification of the circuit shown in Fig. 2;

Fig. 4 is a further diagrammatic illustration of modification of the arrangement shown in Fig. 2, and

Fig. 5 is a still further modification of the arrangement shown in Fig. 2.

The subject control in its preferred form employs a servomotor, usually an upright hydraulic cylinder, having a port communicating with the outlet of a first or up direction positive displacement, rotary hydraulic pump and also with the inlet of a second similar pump. The inlet of the first pump and the outlet of the second pump are connected to a hydraulic storage tank, which preferably also contains air under pressure sufficient to partially counterbalance the load on the servomotor. Valve means are provided for insuring against the interruption of liquid feed to either pump, to relieve overloads, and to maintain the cylinder or servomotor in position when both pumps have been stopped. Both pumps are coupled directly to unidirectional motors, both of which are preferably of the shunt wound direct current type.

When connected in conventional manner, shunt

2

wound direct current motors revolve at a constant speed. The speed of such motors may be increased by reducing the strength of the shunt field, or decreased by reducing the current flowing to the armature.

It will be noted that the cylinder, or servomotor, moves upwardly when the volume discharge or output of the first pump exceeds the output of the second pump, and moves downwardly by gravity when such condition is reversed. If the servomotor operates to move an electrode arm and electrode, it will be obvious that the electrical energy in the air circuit varies inversely with the length of the arc and is therefore proportionate to the position of the electrode. Thus, by controlling properly the speed of one, or both, of the motors, the subject device may be made to maintain the current in the arc circuit at a substantial constant value. Such regulation may be obtained by connecting a transformer or the like between the electrode circuit and ground, and the output employed to regulate the speed of one or both of the pump motors. Similarly, a current transformer, inductively coupled to the electrode circuit, may be employed for the same purpose, or the two may be combined.

For example, the output of the current transformer will be at a maximum when the arc length is at a minimum, and at the same time the output of the potential transformer, connected from the electrode circuit to ground, will be at a minimum. Under such conditions, the length of the arc should be increased. The output or signal from the current transformer may therefore be utilized to supply current to the armature of the first motor, thereby increasing its speed directly with the output, or to the field of the second motor, the speed of which will decrease with an increase of current, or to both simultaneously. In either event, the changes in speed will result in an upward movement of the electrode and an increase in the arc length. This action may, at the option of the operator, be supplemented by connecting the secondary winding of the potential transformer to the armature of the second motor, or to the field of the first motor, or both, depending upon the degree of responsiveness required from the system. Thus, when an increase in arc length is required, the speed of the first motor may be increased either by reducing the strength of the motor field, increasing the current to the armature, or both. Separately or simultaneously with this action, the speed of the second motor may be reduced by increasing the strength of the second motor field, or decreasing

the current to the armature of the second motor, or both.

Fig. 1 illustrates a structure of the type described applied to a direct arc electric melting furnace. A power transformer, generally designated 10, of conventional design is usually provided with inductance winding 11 in the transformer primary. Ordinarily, the transformer 10 will be of the three phase type, each of the three phases being connected to an electrode. For simplicity of illustration, only a single electrode is illustrated, it being understood that the other electrodes are substantial duplicates of that shown. The output current of the transformer 10 is delivered by rigid conductors 12 through a transformer room wall 13 to flexible conductors 14, which are in turn coupled to conductive members 16 connected to an electrode 17, supported on an electrode arm 18. The electrode arm 18 includes an upright member 19 guided for vertical reciprocating movement by a plurality of rollers 21. Within the member 19 is an upright hydraulic cylinder 22 having reciprocable ram 23 engaging the electrode arm 18 in such manner that extension of the ram 23 forces the arm 18, together with the electrode 17, upwardly.

The cylinder 22 is provided with a port or ports 24 near its bottom communicating with hydraulic conduits 26 and 27. The conduit 26, which is connected with the conduit 27 either directly or through the cylinder 22, is connected to the outlet of a first positive displacement rotary hydraulic pump 28, suitably of the gear or vane type. The conduit 27 communicates with the inlet of a second pump 29, similar to the pump 28, but usually having a capacity approximately twice that of the pump 28. A conduit 31 connects an accumulator 32 with check valves 33 and 34, the former communicating with the inlet of the first pump 28, and the latter with the inlet of the second pump 29. A spring loaded check valve 36 connects the outlet of pump 28 with the accumulator 32, a similar valve 37 connecting the outlet of the pump 29 with the accumulator. Although not essential, I prefer to maintain in the accumulator 32 a quantity of air under pressure sufficient to partially counterbalance the weight of the electrode arm 18 and the movable parts associated therewith.

In operation, the pump 28 is continuously driven in one direction only to supply hydraulic fluid to the cylinder 22. The second pump 29 also operates continuously in a single direction to withdraw hydraulic fluid from the cylinder 22, discharging back into the accumulator 32. Thus, it will be apparent that if the discharge rate of the first pump 28 exceeds the discharge rate of the pump 29, the electrode arm 18 and the electrode 17 will be moved upwardly. Conversely, if the discharge rate of the second pump 29 exceeds the discharge rate of the first pump 28, the electrode arm 18 will move downwardly by gravity.

The current flowing in the secondary or arc circuit, which includes the electrode 17, varies with the length of the arcing gap or arc, which may be considered as the distance from the point of the electrode to a conductive charge 38 in the furnace shell 39. As the length of the arc increases, the current is reduced, and as the length of the arc is reduced the current increases. If, therefore, the speed of either of the pumps 28 or 29, or both, may be made to respond proportionately and in the same sense as the current variation in the electrode circuit, the hydraulic

mechanism described will act to maintain the current flow in the electrode circuit substantially constant.

Fig. 2 illustrates diagrammatically electrical means for obtaining such control. It is contemplated in this instance that a shunt wound direct current motor, generally designated 41, having an armature 42 and field winding 43, will be coupled directly to the first pump 28. A similar motor, generally designated 44, having an armature 46 and a field 47, is coupled directly to the second motor 29. Leads 48 and 49 are connected to a suitable constant source of direct current, the field windings 43 and 47 being connected thereto in parallel in such manner as to insure constant field energization. A current transformer 51 is coupled inductively to the arc circuit, as to the electrode conductor 12, the output being connected to a suitable rectifier 52, such as the dry plate type. The output of the rectifier 52 is connected in series with the armature 42 across the constant current leads 48 and 49 in such manner that the voltage output of the rectifier 52 will be added to the voltage in the leads 48 and 49. A variable resistance 53 may be employed to regulate the flow of direct current in this circuit, although it will be understood that other means of current regulation on either the direct current or alternating current side of the rectifier 52 may be substituted therefor. The values of the maximum voltage output of the rectifier 52 during operation and of the line 48-49 should be such that when each is at a maximum value the sum of the two is equal to the maximum voltage for which the motor 41 is designed.

The charge 38 in the shell 39 is suitably grounded as at 54. A potential transformer 56 has a primary winding 57 connected between the electrode conductor 12 and the ground 54. The output of the secondary 58 of the potential transformer 56 is passed through a rectifier 59, the output of which is passed through the armature 46 of the motor 44. A variable resistance 61 may be placed in series in the output circuit of the rectifier 59 to control the current passing through the armature 46.

In operation, it will be noted that the motors 44 and 41 will revolve continuously in the same direction and will vary only in speed. In each instance, the fields are of constant strength and virtually the entire speed regulation of these motors is obtained by varying the armature current. In the case of the motor 41, the armature 42 will always be supplied with a predetermined minimum direct current voltage, this voltage being supplemented by the output of the rectifier 52 when the transformer 51 is energized. The degree of energization of the current transformer 51 is, of course, dependent upon the current flowing through the conductor 12 and will therefore vary between zero and some maximum value. As the electrode 17 approaches the charge 38, assuming an arc to exist, the current flowing through the bus bars 12 will increase, thereby increasing the speed of the motor 41 and increasing the discharging volume of the pump 28. Also, as the arc shortens, the current flowing through the primary winding 57 of the transformer 56 is reduced, thus reducing the amount of current flowing through the armature 46 of the motor 44 which, of course, reduces the speed of this motor. It will thus be seen that by a change in the intensity of current, the speed of the first motor is increased and the speed of the second motor is decreased, these variations act-

ing in unison to move the electrode arm 18 upwardly and increase the length of the arc. It is not necessary to supply a predetermined minimum current into the armature 46 since the output of the transformer 56 will not drop to zero in normal operation.

It is not necessary in every instance to vary speed of both motors, since a variation in the speed of either can be made to produce the desired electrode movement at a rate proportional to the variation in electrode current from a predetermined or selected normal. As illustrated in Fig. 3, the motor 41 is connected directly to the constant direct current supply lines 48-49. The field 43 and the armature 42 being connected in shunt or parallel as indicated in such manner as to drive the motor 41 at a constant speed. A current transformer 51 conductively coupled to the conductor 12 energizes a rectifier 52. The output of the rectifier 52 is placed in series with the constant voltage supply 48-49 and with the field winding 47 of motor 44 in such manner that the field winding 47 will at no time fall to a voltage below that supplied from the lines 48-49. The potential transformer 56, as in the previous illustration, energizes the rectifier 59, which in turn energizes the armature 46 of the motor 44.

In this instance, it will be noted that the motor 41, being connected in shunt, will operate at a substantially constant speed supplying hydraulic fluid at a predetermined rate to the cylinder 22. The speed of the second motor 44, which removes liquid from the cylinder 22, varies inversely with the current flowing through the conductor 12. For example, should the current in the conductor fall, the output of the rectifier 52 will be reduced. Since the output of the rectifier 52 is in series with the direct current supply 48-49, thereby supplementing such voltage, the voltage normally supplied to the field winding 47 will be reduced, thus increasing the speed of the motor 44. Since the reduction in current in the conductor 12 is the result of an increased voltage drop across the arc of the electrode 17, the output of the transformer 56 and the rectifier 59 will increase, thereby increasing the current to the armature 46. This also is effective in increasing the speed of the motor 44, both signals operating, of course, in such manner as to reduce the voltage drop across the arc by lowering the electrode, thereby restoring the current in the conductor 12 to normal.

The control principle illustrated in Fig. 3 can be applied similarly to the motor 41, as illustrated in Fig. 4. In this instance, the motor 44 is connected in conventional manner to a substantially constant source of direct current, the field 47 being connected in shunt with the armature 46. The substantially constant direct current source 48-49 is, as previously described, connected in series with the rectifier 52 in such manner that the voltages are additive. The rectifier 52 is energized by the current transformer 51 as previously described, the output of the rectifier 52 being passed through the armature 42 of the first motor 41. The output of the potential transformer 56 is, as before, rectified by the rectifier 59, the output of which energizes the field winding 48 of the motor 41. In this instance an increase in current increases the energization of the armature 42 through the current transformer 51, and decrease the strength of the field 43 through the transformer 56, thus increasing the speed of the motor 41 and length-

ening the arcing gap between the electrode 17 and the charge 38.

I have illustrated the application of the control to either of the two motors and to the armatures of the two motors in such manner as to simultaneously increase and decrease the relative speeds of the motors as required. When employing the type of motor herein described, namely, a shunt wound direct current motor, the output of the current transformer 51 may be connected to either the armature of the first motor, the field of the down motor, or both. The output of the potential transformer may similarly be connected to the armature of the second motor, the field of the first motor, or both. In addition, both may be used simultaneously as illustrated in Fig. 5. For convenience of illustration, two separate sources of substantially constant direct current 48-49 and 48¹-49¹ are illustrated. As in previous examples, current transformer 51 is inductively coupled to the conductor 12 and energizes rectifier 52, which in turn energizes the armature 42 of the first motor 41. The armature 42 is connected in series with a source of direct current 48¹-49¹, the field 47 of the second motor 44 also being placed in series in this circuit. It will be noted that the field 47 is at all times energized. The potential transformer 56 energizes rectifier 59, the output of which is connected with the armature 46 of the motor 44. The armature 46 is in series with the direct current source 48-49 and with field 43 of the motor 41.

In this instance, a decrease in current in the conductor 12 reduces the speed of the first motor by reducing the armature current and increases the speed of the second motor by reducing the current flowing in the field 47. Simultaneously, the output of the transformer 56 and rectifier 59 are increased, which increases the current to the armature 46 of the motor 44, thus increasing its speed. The increase in the output of rectifier 59 also increases the strength of the field 43 of the motor 41, which further reduces the speed of this motor. The length of the arc is therefore rapidly reduced and the current flow in the conductor 12 restored to normal.

In each instance, it will be noted that an auto transformer or similar regulating device may be employed to regulate the output of the transformer 51 and 56 in accordance with conventional practice. It will also be understood that other forms of motors may be employed and suitable modification made in the circuit to accommodate these various motor types without departure from the true spirit and scope of this invention.

The various hydraulic, mechanical and electrical arrangements hereinbefore described are applicable to a single phase of a three phase furnace, the other phases being substantial duplicates of that described. It will also be appreciated that by properly selecting motor voltages in comparison with arc circuit voltages the transformer 56 may in some instances be eliminated and the alternating current drawn from the electrode circuit rectified directly by the rectifier 59. This usually is not considered desirable, however, since the various motor windings energized by the output of the rectifier 59 must be constructed to carry relatively high amperage, low voltage current and are therefore usually more expensive.

It will be apparent from study of the control herein described that both motors may have the same maximum operating speed if the pumps

vary in size. Also, by using motors having different maximum operating speeds, the pumps may be of the same size. In either event and regardless of whether the discharge volumes of one or both pumps vary, there must be a point at which the discharge volume of the first pump equals the discharge volume of the second pump, this being the condition obtained when the arc is operating stably in the desired arc length.

I claim:

1. In an electric arc melting furnace of the type having an electrode movable for varying the arcing gap, conductor means for supplying electric current to the electrode and liquid servomotor means coupled to the electrode for varying the electrode position, the improvement which includes first and second rotary positive displacement hydraulic pumps driven respectively by first and second unidirectional motors, the first pump having an outlet communicating with said servomotor and with the second pump inlet, a liquid reservoir communicating with the first pump inlet and the second pump outlet, and means responsive to variation in the arcing gap of the electrode for varying the speed of one of the motors through a range including an intermediate speed at which the output of the first pump equals the output of the second pump, said last mentioned means including a transformer inductively coupled to said electrode conductor and to said motor.

2. In an electric arc melting furnace of the type having an electrode movable for varying the arcing gap, conductor means for supplying electric current to the electrode and liquid servomotor means coupled to the electrode for varying the electrode position, the improvement which includes first and second rotary positive displacement hydraulic pumps driven respectively by first and second unidirectional motors, the first pump having an outlet communicating with said servomotor and with the second pump inlet, a liquid reservoir communicating with the first pump inlet and the second pump inlet, and means responsive to variation in the arcing gap of the electrode for varying the speed of the first motor through a speed range including an intermediate speed at which the discharge volumes of the first and second pumps are equal, said means including a current transformer inductively coupled to the electrode conductor means and connected to said first motor, thereby varying the speed of said first motor directly with and proportionately to the current flow in the conductor means.

3. In an electric arc melting furnace of the type having an electrode movable for varying the arcing gap, conductor means for supplying electric current to the electrode and liquid servomotor means coupled to the electrode for varying the electrode position, the improvement which includes first and second rotary positive displacement hydraulic pumps driven respectively by first and second unidirectional motors, the first pump having an outlet communicating with said servomotor and with the second pump inlet, a liquid reservoir communicating with the first pump inlet and the second pump outlet, and means responsive to variation in the arcing gap of the electrode for varying the speed of the second motor through a speed range including an intermediate speed at which the discharge volumes of the first and second pumps are equal, said means including the current transformer inductively coupled to the electrode conductor

means and connected to said second motor thereby varying the speed of said motor inversely and proportionately to the current flow in the electrode conductor means.

5. In an electric arc melting furnace of the type having an electrode movable for varying the arcing gap, conductor means for supplying electric current to the electrode and liquid servomotor means coupled to the electrode for varying the electrode position, the improvement which includes first and second rotary positive displacement hydraulic pumps driven respectively by first and second unidirectional motors, the first pump having an outlet communicating with said servomotor and with the second pump inlet, a liquid reservoir communicating with the first pump inlet and the second pump outlet, and means responsive to variation in the arcing gap of the electrode for simultaneously varying the speed of both of said motors through a range including an intermediate point at which the discharge of the first pump is equal to the discharge of the second pump, said means including the current transformer inductively coupled to the electrode conductor means and connected to both the first and second motors.

5. In an electric arc melting furnace of the type having an electrode movable for varying the arcing gap, conductor means for supplying electric current to the electrode and liquid servomotor means coupled to the electrode for varying the electrode position, the improvement which includes first and second rotary positive displacement hydraulic pumps each having an inlet and an outlet, the outlet of the first pump communicating with said servomotor means and with the second pump inlet, a reservoir communicating with the first pump inlet and the second pump outlet, first and second motors coupled respectively to said first and second pumps, said first motor being a direct current shunt wound motor having a field winding and an armature winding and means responsive to variation in the arcing gap for varying the speed of the first motor through a range including an intermediate speed at which the discharge volumes of the two pumps are equal, said means including a current transformer inductively coupled to the electrode conductor means, means rectifying the output of the current transformer and means supplying such rectified current to the armature winding of said first motor.

6. In an electric arc melting furnace of the type having an electrode movable for varying the arcing gap, conductor means for supplying electric current to the electrode and liquid servomotor means coupled to the electrode for varying the electrode position, the improvement which includes first and second rotary positive displacement hydraulic pumps each having an inlet and an outlet, the outlet of the first pump communicating with said servomotor means and with the second pump inlet, a reservoir communicating with the first pump inlet and the second pump outlet, first and second motors coupled respectively to said first and second pumps, said second motor being a direct current shunt wound motor having a field winding and an armature winding and means responsive to variation of the arcing gap for varying the speed of the second motor through a range including an intermediate speed at which the discharge volumes of the two pumps are equal, said means including a current transformer inductively coupled to the electrode conductor means, means rectifying the output of the

current transformer and means supplying such rectified current to the field winding of said second motor.

7. In an electric arc melting furnace of the type having an electrode movable for varying the arcing gap, conductor means for supplying electric current to the electrode and liquid servomotor means coupled to the electrode for varying the electrode position, the improvement which includes first and second rotary positive displacement hydraulic pumps each having an inlet and outlet, the outlet of the first pump communicating with said servomotor means and with the second pump inlet, a reservoir communicating with the first pump inlet and the second pump outlet, first and second motors coupled respectively to said first and second pumps, both said first and second motors being direct current shunt wound motors, each having field windings and an armature winding, and means responsive to variation of the arcing gap for varying the speeds of said motors through ranges including an intermediate point at which the discharge volumes of the two pumps are equal, said means including a current transformer inductively coupled to the electrode conductor means, means rectifying the output of the current transformer and means supplying such rectified current to both the armature winding of the first motor and to the field winding of the second motor.

8. The structure defined in claim 5 which includes means maintaining a constant minimum energization of the armature of the first motor.

9. The structure defined in claim 6, which includes means for maintaining a constant minimum energization of the field winding of the second motor.

10. In an electric arc melting furnace of the type having an electrode movable for varying the arcing gap, conductor means for supplying electric current to the electrode and liquid servomotor means coupled to the electrode for varying the electrode position, the improvement which includes first and second rotary positive displacement hydraulic pumps, each having an inlet and an outlet, the outlet of the first pump communicating with said servomotor means and with the second pump inlet, a reservoir communicating with the first pump inlet and the second pump outlet, first and second motors coupled respectively to said first and second pumps, both of said motors having direct current shunt field and armature windings and means proportionately responsive to variation in the arcing gap of the electrode for varying the speeds of the motors inversely through a range including a point at which the discharge volume of the first pump equals the discharge volume of the second pump, said last mentioned means including a current transformer inductively coupled to the electrode conductor means, means rectifying the output of the current transformer, means transmitting such rectified current to the armature of the first motor and to the field of the second motor, a potential transformer connected from the electrode conductor means to ground, means for rectifying the output of said potential transformer, and means transmitting the rectified output of said potential transformer to the armature of the second motor and to the field of the first motor.

11. The structure in claim 10 which includes means maintaining a predetermined minimum

degree of energization on the fields of both motors.

12. In an electric arc melting furnace of the type having an electrode movable for varying the arcing gap, conductor means for supplying electric current to the electrode and liquid servomotor means coupled to the electrode for varying the electrode position, the improvement which includes first and second rotary positive displacement hydraulic pumps, each having an inlet and an outlet, the outlet of the first pump communicating with said servomotor means and with the second pump inlet, a reservoir communicating with the first pump inlet and the second pump outlet, first and second motors coupled respectively to said first and second pumps, both of said motors having direct current shunt field and armature windings and means proportionately responsive to variation in the arcing gap of the electrode for varying inversely the speeds of the motors through a range including a point at which the discharge volume of the first pump equals the discharge volume of the second pump, means for constantly energizing the fields of the first and second motors, a current transformer inductively coupled to the electrode conductor means, means rectifying the output of the current transformer, means transmitting such rectified output to the armature of the first motor, a potential transformer connected from the electrode conductor to the ground, means rectifying the output of said potential transformer and means transmitting the rectified output of the potential transformer to the armature of the second motor.
13. In an electric arc melting furnace of the type having an electrode movable for varying the arcing gap, conductor means for supplying electric current to the electrode and liquid servomotor means coupled to the electrode for varying the electrode position, the improvement which includes first and second rotary positive displacement hydraulic pumps, each having an inlet and an outlet, the outlet of the first pump communicating with said servomotor means and with the second pump inlet, a reservoir communicating with the first pump inlet and the second pump outlet, first and second motors coupled respectively to said first and second pumps, means for driving the first motor at a substantially constant speed, the second motor being direct current shunt wound motor having a field winding and an armature winding, and means proportionately responsive to variation in the arcing gap of the electrode for varying the speed of the second motor through a range including a speed at which the discharge volume of the first pump equals the discharge volume of the second pump, said means including a current transformer inductively coupled to the electrode conductor means, means rectifying the output of the current transformer, means transmitting such rectified output to said second motor field, means maintaining a predetermined minimum degree of energization on said second motor field, a potential transformer connected from the electrode conductor to ground, means rectifying the output of said potential transformer and means transmitting the rectified output of said potential transformer to the armature of said second motor.
14. In an electric arc melting furnace of the type having an electrode movable for varying the arcing gap, conductor means for supplying electric current to the electrode and liquid servomotor means coupled to the electrode for varying the electrode position, the improvement which

11

includes first and second rotary positive displacement hydraulic pumps each having an inlet and an outlet, the outlet of the first pump communicating with said servomotor means and with the second pump inlet, a reservoir communicating with the first pump inlet and the second pump outlet, first and second motors coupled respectively to said first and second pumps, means for driving said second motor at a substantially constant speed, said first motor having a direct current shunt field and direct current armature and means proportionately responsive to variation in the arcing gap of the electrode for varying the speed of said first motor through a range including a point at which the discharge volume of the two pumps are equal, said means including

12

a current transformer inductively coupled to the electrode conductor means, means rectifying the output of the transformer, means transmitting such rectified output to the armature of said first motor, a potential transformer connected from electrode conductor to ground, means rectifying the output of such potential transformer, and means transmitting the rectified output of said potential transformer to the field of the first motor, and means for maintaining a predetermined degree of energization on the field winding of the first motor.
